UNITED STATES PATENT OFFICE

FRANK A. HOWARD, OF ELIZABETH, NEW JERSEY, ASSIGNOR TO STANDARD OIL DEVELOPMENT COMPANY, A CORPORATION OF DELAWARE

DISTILLATION OF HYDROCARBONS

Application filed July 10, 1924. Serial No. 725,154.

This invention relates to the distillation of hydrocarbons, and will be understood from the following description, taken in connection with the accompanying drawings in which Fig. 1 represents in side elevation, partly in section, one form of apparatus which may be employed, and Fig. 2 is a fragmentary view showing distilling means.

In the customary practice of distilling petroleum, the crude oil is heated to a vaporizing temperature and a light distillate is taken off, the temperature is further raised and a heavier distillate is taken off, and so on progressively, the temperature being successively higher and the distillate cuts successively heavier. Toward the end, in taking off lubricating distillate cuts there is increasing difficulty in limiting damage from overheating, and resort is usually had at this stage to the expedient of introducing steam or reducing pressure. Even at best, in the operation of prior methods more or less destruction of the lubricating constituents occurs through overheating.

In accordance with my invention, the distillation conditions are so arranged as to produce a relatively low boiling material containing the lubricating oils by vaporizing off collectively the light constituents and heavy constituents in one wide cut. This may then be fractionated at temperatures below that at which objectionable decomposition occurs.

Referring more particularly to the drawings, the numeral 1 designates a heating chamber fired by any convenient means and containing a conduit or coil 2 through which oil is passed to be heated. Steam may also, if desired, be introduced into the oil in the conduit through a connection (not shown). From the heating conduit, a connection containing a valve 4 leads to a vaporizing chamber 3. Steam may be passed through a suitable connection into this chamber, instead of into the conduit, if desired.

The vaporizing chamber contains a cooling coil 5, a collecting pan 6 connected by line 10 with a receiving tank 11, a final cooler 12, and a collecting tank 13. The vaporizing chamber is connected near the top thereof by line 14 with a barometric condenser 15, wherein

any steam or light oils are practically completely condensed and pass into sump 16. The barometric condenser is also connected by line 17 with a surface cooler 18 wherein any remaining condensable vapors are separated out and removed as condensate by pump 20.

The entire system, exclusive of the heating coil, is maintained under suitable pressure, preferably below atmospheric pressure, by means of pump 9 joined by line 19 to the surface cooler 18. The pressure may vary rather widely. Goods results are ordinarily obtained when the absolute pressure corresponds to a mercury column of about 2 inches. The condensate receiving tank 13 or the receiving tank 11 may also be joined by a line direct to the vacuum pump, if desired, but ordinarily the construction shown operates satisfactorily to accomplish the object in view.

In Fig. 2 there is illustrated a still 21 which receives the condensate from tank 13 through a line 22 in which there is a pump 23. The still is suitably fired to expel the low boiling constituents which pass off through vapor line 24. The lubricants are withdrawn through a line 25. It will be understood that any suitable equipment may be provided for receiving the low boiling constituents and the lubricants.

In the operation of the process, crude oil is forwarded from any desired source through the heated conduit 2 and the temperature of the oil is raised sufficiently to produce the subsequent vaporization desired, but without attaining substantial cracking range. The precise temperature will vary somewhat with the particular oil being operated upon. As an illustration, the oil temperature at the heating conduit outlet may be maintained around 650° F. Passing from the conduit, the oil is released into the vaporizing chamber 3 where under the diminished pressure or vacuum maintained, a flash vaporization occurs due to the contained heat in the oil. This results in producing one wide cut containing all constituents from the lowest boiling up to the heaviest that can be distilled without substantial cracking.

Since the low boiling constituents reduce the effective boiling point for the entire cut,

hydrocarbons can be safely vaporized which otherwise could only be vaporized at temperatures likely to be destructive. Unvaporized residue may be drawn off by pipe 21. The 5 vaporous product passes over to the collecting system where it may be condensed in one collective condensate, or, if desired, the vapors may pass to a fractionating tower (not shown), which may be of plate rectifying column type or simpler type as preferred. Heat 10 may be supplied by steam coils at the bottom of the tower. A lubricating stock condensate may be first taken off and successively lighter fractions condensed in the further zones of 15 condensation.

The following example is illustrative of one method in which the invention may be practiced. A reduced crude oil, such as reduced Colombia crude having an A. P. I. gravity of 20 about 16.5, is passed through the coil 2 and enters the tower 3 at a temperature of 710 to 720° F. The temperature of the oil in the bottom of the tower is about 647° F., the temperature of the vapor stream leaving the 25 tower is about 236° F., and the temperature of the condensate flowing through line 10 is about 403° F. This condensate is composed of one wide cut containing hydrocarbons condensing in general between 236° F. and 30 647° F. It has an A. P. I. gravity of about 22.8, a Saybolt viscosity of about 268 seconds at 100° F., and a flash point of about 335° F. The absolute pressure in the tower is equivalent to about one inch of mercury. The lubricating distillate is withdrawn from tank 13 and separated into the desired fractions in any suitable manner.

While the vapors may be fractionally condensed as described above, I usually prefer to 40 condense them in one collective condensate as described and distill off from these the lighter constituents to effect the desired further separation, including the segregation of lubricating oils.

45 Where employing a crude petroleum having a considerable gasoline content, it is sometimes desirable to distill off in the usual manner a part or all of the gasoline before introducing the oil into the heating conduit.

50 The invention is not limited to the specific embodiment referred to for the purpose of explaining the inventive principle. Various alternative arrangements of procedure and apparatus may be made within the scope of 55 the appended claims.

What I claim is:

1. The improvement in the art of distilling hydrocarbon oil containing lubricating fractions together with lighter constituents, 60 which comprises heating the oil to a high temperature short of substantial cracking in a conduit of restricted cross-section, passing the hot oil into the lower portion of an enlarged vertical zone maintained under pressure sufficiently reduced below the pressure in the con-

duit to permit flash vaporization, by the contained heat of the oil only, of one wide cut containing lubricating fractions together with lower boiling constituents which reduce the effective distillation temperature, and condensing said lubricating fractions within the enlarged vertical zone. 70

2. The improvement in the art of distilling petroleum containing lubricating fractions together with lighter and heavier constituents, which comprises passing the petroleum through a heated conduit of restricted cross-section to raise it to a high temperature short of substantial cracking, thence into the lower portion of a vertical vaporizing chamber 80 maintained under a pressure less than atmospheric, heating the chamber only by the heat of the entering oil, vaporizing in the chamber one wide cut containing all constituents from the lowest boiling to the highest boiling that are removable at the temperature and pressure of the operation, condensing the wide cut with the exception of the lowest boiling components, within the chamber, and collecting the condensed wide cut without permitting the same to commingle with the heavier constituents. 85

3. The improvement in the art of distilling petroleum oil containing lubricating fractions together with lighter and heavier constituents, which comprises passing the oil through a heated conduit of restricted cross-section to raise the oil to a high temperature short of substantial cracking, thence into the lower portion of vertical vaporizing chamber maintained under a pressure less than atmospheric, heating said chamber by the heat of the entering oil only, vaporizing in said chamber one wide cut containing all constituents from the lowest boiling to the highest boiling that are removable at the temperature and pressure of the operation, condensing the wide cut with the exception of the lowest boiling components, within the chamber, collecting the condensed wide cut in the chamber at a point above that at which the oil enters the chamber, withdrawing the condensed wide cut, and separately removing the residue of heavier constituents from said chamber. 100
